COMBINED FRY PAN AND BROILER

David G. Lord, Unionville, Conn., assignor to Landers,
Frary & Clark, New Britain, Conn., a corporation of Connecticut

Filed Feb. 14, 1964, Ser. No. 78,634

Term of patent 7 years

(Cl. D44—1)

FIG. 1

Des. 199,256

PAGE 2

FIG. 2

Des. 199,256

FIG. 3

FIG. 5

I claim:

The ornamental design for a combined fry pan and broiler, as shown and described.
